UNITED STATES PATENT OFFICE

171,967

CHORD PLAYING DEVICE FOR KEYBOARD INSTRUMENTS

Felix M. De Cola, Hollywood, Calif.

Application December 20, 1952, Serial No. 22,800

Term of patent 14 years

(Cl. D56—1)

To all whom it may concern:

Be it known that I, Felix M. De Cola, a citizen of the United States of America, residing at 736 North Martel Avenue, Hollywood 46, in the county of Los Angeles, State of California, have invented a new, original, and ornamental Design for a Chord Playing Device for Keyboard Instruments, of which the following is a specification, reference being had to the accompanying drawing, forming a part hereof.

Figure 1 is a perspective view of a chord playing device for keyboard instruments, showing my new design;

Figure 2 is a rear elevational view thereof; and Figure 3 is a side elevational view of the same.

I claim:

The ornamental design for a chord playing device for keyboard instruments, as shown.
